UNITED STATES PATENT OFFICE.

ALEXANDER LEVIN AND JOSEPH MEDIN, OF CALUMET, MICHIGAN.

DESIGN FOR A WATCHCASE.

53,418.

Specification for Design.

Patented June 10, 1919.

Application filed March 10, 1919. Serial No. 281,879. Term of patent 7 years.

To all whom it may concern:

Be it known that we, **ALEXANDER LEVIN** and **JOSEPH MEDIN**, citizens of the United States of America, residing at Calumet, in the county of Houghton and State of Michigan, have invented a new, original, and ornamental Design for Watchcases, of which the following is a specification, reference being had to the accompanying drawings, forming part thereof.

The figure is an elevational view of a watchcase showing our new design.

We claim—

The ornamental design for a watchcase, as shown.

**ALEXANDER LEVIN.
JOSEPH MEDIN.**
